United States Patent Office

Des. 217,576
Patented May 12, 1970

217,576

SAFETY PAPER OR SIMILAR ARTICLE

Carl Couve, Rolling Meadows, Ill., assignor, by mesne assignments, to The Mead Corporation, Dayton, Ohio, a corporation of Ohio

Filed Mar. 21, 1969, Ser. No. 16,368

Term of patent 14 years

Int. Cl. D19—05

U.S. Cl. D59—6

FIG. 1

FIG. 2

FIG. 1 is a plan view of a safety paper showing my new design; and

FIG. 2 is an enlarged fragmentary view thereof.

I claim:

The ornamental design for a safety paper or similar article, as shown.
